UNITED STATES PATENT OFFICE.

LEO L. PFEIFER, OF COLUMBUS, OHIO, ASSIGNOR TO THE JOHN W. BROWN MANUFACTURING COMPANY, OF COLUMBUS, OHIO, A CORPORATION OF OHIO.

BUFFING OR POLISHING MACHINE.

1,233,701.

Specification of Letters Patent. Patented July 17, 1917.

Application filed November 15, 1916. Serial No. 131,366.

To all whom it may concern:

Be it known that I, LEO L. PFEIFER, a citizen of the United States, residing at Columbus, in the county of Franklin and State 5 of Ohio, have invented certain new and useful Improvements in Buffing or Polishing Machines, of which the following is a specification.

This invention relates to buffing or polishing machines of the type used for finishing the interior or reflecting surfaces of searchlights or headlights particularly those used in connection with motor vehicles. Also, my invention is directed toward and an improvement over that type of machine illustrated in my co-pending application Serial Number 115119, filed August 16, 1916.

The main object of this invention resides in the combination of a die and polishing head or member capable of a relative rotative movement when the two are brought together with a reflector between them, with a pocket or channel structure inset slightly from the face of the plunger to allow the pocketing or circulation of a polishing liquid in order that an adequate supply may at all times be had to coöperate with the abrading surfaces. Specifically, my invention also has for its object the radial arrangement of abrading members upon the polishing head in such manner that they protrude slightly beyond the face of the polishing head to, in this manner, present channels between the abrading members. This type of polishing head used in combination with a die and means for permitting the free circulation of a polishing liquid between the die and polishing head produces a highly effective type of machine.

The preferred embodiment of my invention is shown in the accompanying sheet of drawings, in which similar characters of reference designate corresponding parts, and in which:

Figure 1 is a view mainly in side elevation but showing the die in section of my improved type of polishing machine,

Fig. 2 is a bottom face view of my improved type of polishing head designed for use in connection with this machine, and,

Fig. 3 is an enlarged fragmentary section of a portion of the head showing the manner in which the abrading strips are held in position.

In the drawings, the machine is shown as

constituting a main framework, of which the portion 2 forms the base and from which there extends vertically a bracket portion 3 having a journal portion 4 at its outer end. Within this journal portion there is rotatably mounted a shaft 5 and upon the upper end of this shaft there is rigidly secured a pulley 6 by means of which the driving power may be supplied thereto and upon the lower end thereof there is mounted my improved type of chuck or polishing head 7. This polishing head is designed to coöperate with a die 8 which may be of any preferred material, but which is formed with a concavity 9 so shaped to snugly fit the reflector member 10. Also, this die is provided with a series of passageways 11 which lead to the central aperture 12 within the lining member 13 and which also communicate with the interior of the receptacle 14 at 70 their outer ends. This receptacle is designed to be supplied with a polishing liquid of the desired character and by means of the passageways, this polishing liquid may have access to or freely circulate between the 75 polishing head and the reflector being polished. This receptacle itself is securely mounted upon the shaft 15 which shaft is movable vertically through its bearing 16 in the base portion 2. I have illustrated a 80 simple type of movement consisting of a link 18 pivotally secured at its lower end at 19 to the shaft and pivotally secured at its upper end at 20 to the lever arm 21. This lever is rigidly secured to a stub shaft 22 85 and each time this stub shaft is oscillated by means of the handle 23, the receptacle is given a vertical movement. It is essential only that the die and polishing head be relatively movable to bring them together and it 90 will, therefore, be understood that any manner of structure for accomplishing this is considered by me to be within the scope of the appended claims.

The head 7 is itself of paraboloidal shape 100 to fit the parabolic reflector worked upon. This head is provided with a series of radial slots 24 of a size to accommodate the abrading members 25. These abrading members are of any desired material such, for instance, as leather or some other pliable material capable of adjusting itself to the shape of the interior of the reflector. Also, these members project slightly beyond the face of the head to thereby create spaces 26 be- 110

5
tween them in which spaces the polishing liquid is either allowed to collect or to freely flow during the normal operation of the device. The circulation depends a great deal upon the speed at which the polishing head is rotated, the liquid circulating under the influence of this rotation and in such circulation, a fresh supply is always on hand to supply the necessary polishing ingredients. 10 These abrading strips are removably secured in position by a plurality of screws 27 which clamp them in a position after the manner shown in Fig. 3. Thus, after the abrading members become worn, they 15 may be very readily removed and replaced by simply loosening the screws 27 and then again moving them into clamping position.

20 From the foregoing description, it will be apparent that I have provided a type of machine in which the abrading members may be renewed as may be found necessary. Also, by so constructing and arranging these abrading members that they project beyond the surface of the polishing head and form 25 channels, a space is provided wherein the polishing liquid may either collect or circulate, in which manner a uniform supply of polishing ingredient may at all times be had.

25 What I claim, is:

30 1. A polishing machine of the character described comprising a die element and a polishing head element, one of said elements being formed with abrading portions and pocket portions, means for causing a relative rotation between said two elements when they are together with the object to be 35 polished between them, and means whereby said pocket portions are maintained in constant supply with a polishing liquid when 40 said two elements are together.

45 2. A polishing machine of the character described comprising a die, a polishing head

formed with abrading portions and pocket portions, means for causing a relative rotation between the die and head when they 45 are together with a reflector between them, and means whereby said pocket portions are maintained in supply with a polishing liquid when the die and head are together.

50 3. A polishing machine of the character described comprising a die, a polishing head formed with abrading portions and depressed channels between abrading portions arranged to permit a free flow of a polishing liquid therethrough, and means for causing a relative rotation between the die and head when they are together with a reflector 55 between them.

55 4. A polishing machine of the character described comprising a concaved die, a polishing head, removable abrading strips secured in said head and projecting outwardly therefrom to form channels through which a polishing liquid may flow, means whereby a polishing liquid may be fed to said channels, 60 and means for causing a relative rotation between said die and head when they are together with a reflector between them.

65 5. A polishing machine of the character described comprising a die, a polishing head, removable pliable abrading members on said head, means for causing a relative rotation between said die and head when they are together with a reflector between them, and means whereby a circulation of polishing 70 liquid may be maintained between said die and head when such relative rotation occurs.

75 In testimony whereof I affix my signature in presence of two witnesses.

LEO L. PFEIFER.
